Inventor:

Walter T. Abel,
by Parker C. Atty.

UNITED STATES PATENT OFFICE.

WALTER T. ABEL, OF WATERBURY, CONNECTICUT, ASSIGNOR TO THE PATENT BUTTON COMPANY, OF WATERBURY, CONNECTICUT, A CORPORATION OF CONNECTICUT.

BUTTON.

Application filed January 5, 1927. Serial No. 159,108.

My invention relates to new and useful improvements in tack buttons and has for an object to provide a button that is extremely efficient in service, comprising but few parts 5 and relatively cheap to assemble and manufacture.

One of the principal objects of the invention is to provide a button comprising but three parts and a tack to hold the button 10 securely to the cloth or other material to which it is to be fastened.

In buttons of a similar type as a rule the body of the button is provided with an anchor and an anvil plate, over which plate 15 is placed the cap or head of the button, as in the patent to F. R. White, number 1,417,646 of 1922.

In the present instance, I employ a body portion, an anchor and a cap, the anchor 20 holding the tack in its deformed and locked position, and the anchor also acting as a central support for the cap or top plate.

Still another object of the invention is to provide a metal button in which there is 25 forced a small hollow anchor or vise having tapered sides, the walls of the anchor being formed of a relatively hard metal. The bottom wall of the anchor is perforate, that is, it is provided or so formed that it has a small 30 opening therein, while the top wall has a depression therein, so that the resultant projection on the inner side of the chamber will deflect the tack when forced into the anchor.

With these and other objects in view, the 35 invention consists in certain new and novel arrangements and combination of parts which will be hereinafter more fully described and pointed out in the claim.

Referring now to the drawings showing a 40 preferred embodiment of my invention.

Fig. 1 is a sectional view showing the button, a portion of a garment and a tack, before the tack has been forced into the button.

Fig. 2 shows a plan view of a button and 45 tack, a button and the anchor being then shown in elevation and then a section through the button and tack.

Fig. 3 is a top plan view of the button 50 with the cap removed, and the anchor in place.

Fig. 3^a is a sectional view showing the same parts as Fig. 3.

Fig. 3^b is a bottom plan view of the same.

Figs. 4 and 4^a are views of the cap member in plan and section respectively and before being swedged. 55

Fig. 5 is a sectional view of the anchor.

Fig. 5^a is a bottom plan view of the same, and

Fig. 6 is a plan view of the tack. 60

Referring now more particularly to the several views, there is shown one form of improved button, comprising a body portion 1, which is formed of relatively cheap, thin and soft metal, such as brass, aluminum or in fact any similar relatively soft metal. 65 This body portion is provided with a hub 2, then flares outwardly at 3 and slightly upwardly and outwardly as at 4, to form a rim over which will be placed a cap 5, which cap 70 will have its flange 6 pressed inwardly over the rim 4 when the button is in its final shape.

The under surface of the hub is forced or pressed upwardly as at 7 and centrally of the 75 depression, it is pierced as at 8.

Before the cap 5 is placed over the rim of the body of the button, there is tightly forced into this hub a hollow anchor 9, the walls of which are of a relative hard metal, such as 80 iron, so that the prong 10 of a tack 11 will not pierce the same as will be shortly described.

The side walls of the vise or anchor are 85 preferably tapered, so that the anchor may be tightly pressed or forced within the hub 2 of the body of the button 1, as may be clearly seen in the several views.

The anchor or vise is preferably formed from a square blank and the four corners of 90 the square blank are turned in on a pin, the diameter of the pin determining the size of the hole or opening in the bottom. The edges or corners extend upwardly as at 13 within the anchor as may be seen in the several views. It might be possible to form the die from a round blank rather than a square one, but in actual practice the die is made from a square blank. 95

On the top surface of this small anchor 100 and centrally thereof, there is formed a small depression 14, so that the metal displaced will project into the chamber of the anchor, this projection being in vertical alignment with the aforementioned opening 105 12 in the bottom of the said anchor.

As may be clearly seen in Fig. 3^a, the opening in the bottom of the hub of the button, the opening in the lower surface of the anchor and the small projection within the anchor are all in vertical alignment.

As before mentioned the small anchor is placed within the hub of the body of the button before the cap is forced into place and the anchor is of such a height that not only does it act as an anchor, as will be shortly mentioned, but it also forms a support for the cap 5 of the button, when the button is in its final form.

The anchors may be properly placed within the hubs of the buttons by a small automatic laminer or riveting machine and the mode of attaching the buttons to the cloth would be as follows:—

The buttons will be placed in one hopper of an attaching machine while the tacks will be placed in their respective hopper. The prong of the tack will be forced through the material G., to which the buttons are to be attached and will then be forced through the opening 7 in the bottom of the hub of the button to then project through the opening 12 in the anchor and will strike the small projection 14 to be deflected thereby. Inasmuch as the anchor is made of relatively hard metal, it will readily deflect the prong and cause it to bend and extend downwardly as seen in the right hand button Fig. 2. The body of the tack will then curl and bind between the side wall of the anchor and the little projections 13 of deformed metal.

The diameter of the prong of the tack will be greater than the diameters of the openings in the hub and the anchor, but these parts being initially perforate permit the tack to force its way into the metal and then deform and deflect within the chamber of the hard metal anchor.

It will be understood that the several figures of the drawing are enlarged with respect to the actual size of the button, but this

is done for the sake of clearness of illustration.

After the tack has been forced within the body of the button and the anchor, it will also not only hold the button to the material, but will tightly hold the anchor within the hub of the body of the button.

From the aforesaid, it will be seen that I have devised a button comprising but three parts and wherein the anchor may be quickly forced within the hub of the body of the button, which anchor forms a locking means with a tack and also acts as a support for the cap of the button.

Furthermore, by this manner, relatively cheap buttons may be manufactured, which buttons may then be placed in button fastening machines and quickly secured to the garment or garments.

Of course the cap of the button may be decorated or may have the trademark or other insignia thereon.

Many slight changes may be made without departing from the spirit and scope of the invention.

I claim—

A button comprising a shell having a hub and a peripheral rim above said hub, a frusto-conical separate chamber wedged downwardly within the hub, the bottom wall of the chamber having an opening and the portions about the opening extending upwardly into the chamber, the bottom hub being pierced and the said opening in alignment with the opening of the chamber, a tack adapted to be forced through said openings, integral means in the chamber and in alignment with said openings for deflecting the prong of the tack to cause the same to curl between the side wall of the chamber and the fractured metal portions about the opening in the bottom of the chamber.

In testimony whereof I affix my signature:

WALTER T. ABEL
